TREATMENT OF PARAFFIN HYDROCARBONS

Arthur R. Goldsby and Eugene E. Sensel, Beacon,
N. Y., assignors, by mesne assignments, to The
Texas Company, New York, N. Y., a corporation
of Delaware

Application June 30, 1939, Serial No. 282,114

10 Claims. (Cl. 260—683.5)

This invention relates to the treatment or reforming of naphthas and has to do particularly with the isomerization of straight run or virgin naphthas to improve the antiknock value and volatility.

Straight run naphthas from paraffinic or mixed base crudes contain large amounts of paraffin hydrocarbons which consist in substantial amount of straight chain hydrocarbons having a relatively low antiknock value. It is an object of the present invention to convert a substantial amount of such straight chain paraffin hydrocarbons into branch chain or isoparaffin hydrocarbons of high antiknock value.

It has been proposed heretofore to isomerize certain normally gaseous hydrocarbons and lower boiling normally liquid hydrocarbons, such as normal butane and normal pentane, to corresponding isoparaffins by contacting the normal paraffins in the liquid or vapor phase at temperatures of zero to 200° C., with certain anhydrous metallic halides, such as chlorides, bromides, etc. of aluminum, zinc, iron, zirconium, tin, barium, columbium, tantalum and boron, and small amounts of hydrogen halides, such as hydrogen chloride, as promoters. It has also been proposed to subject gasoline of boiling range of about 130° to 190° F. to isomerization in the presence of aluminum chloride and hydrochloric acid at temperatures of about 150° to 200° C.

Normal butane may be successfully isomerized to isobutane in the presence of anhydrous metallic halides and hydrogen halides, without a substantial amount of side reactions, providing correct operating conditions are used. In the case of the higher boiling normally liquid hydrocarbons, considerable difficulty is encountered due to cracking and/or other types of side reactions, whereby substantial deterioration of the catalyst is experienced and a substantial proportion of high boiling material outside of the gasoline boiling range is formed.

It has now been found that the side reactions and accompanying deterioration of the catalyst which normally occur with the higher boiling normal paraffins, may be substantially inhibited or minimized by carrying out the isomerization operation in the presence of a large proportion of a low boiling isoparaffin, such as isobutane and isopentane. Moreover, the formation of high boiling material above the gasoline boiling range is avoided. The reactions involved are not fully understood. It is thought that the isoparaffin may inhibit the cracking and the resultant formation of unsaturated hydrocarbon fragments or

olefins; or the isoparaffin may react with the olefins as formed to produce saturated alkylation products; or a combination of the above two reactions may occur.

The catalysts which are useful include any of the active isomerization catalysts, such as metallic halides, preferably used in the presence of small amounts of promoters, such as hydrogen halides. While any of the anhydrous metallic halides which will function as alkylation catalysts are contemplated, for practical purposes aluminum halides, such as aluminum chloride, and aluminum bromide are preferred. Likewise any of the hydrogen halide promoters, such as HCl, HBr, HI and HF, may be used, but it is preferable to use hydrogen chloride. The metallic halide catalyst may be in solid, granular or lump form, or in the case of AlBr₃ at temperatures above 208° F. in liquid form, or supported on a solid absorbent such as synthetic and natural clays, pumice, brick, coke, activated alumina, and activated carbon. The hydrogen halide promoter may be added as such or may be generated in situ from the metallic halide by adding the required amount of water, steam, or alkyl halide which reacts with the metallic halide.

The process may be carried out in a batch or continuous type of operation, and preferably in a continuous operation. The process is preferably conducted as a cyclic operation in which the isoparaffin is recycled together with any portion or all of the hydrogen halide promoter.

The amount of catalyst and promoter will vary, depending on the type of operation used. In a batch operation, it is contemplated that the catalyst may be about 1 to 20% or more by weight based on the weight of the hydrocarbon charge. The promoter may vary between about 0.1 and 5% or more, and preferably about 1%. In continuous operations, wherein the promoter is recycled, the range of the amounts of the catalyst and promoter will be much broader. For example, the amount of catalyst may range from 1 to 100% or more, while the promoter may vary from about 0.05 to 50% or more.

The invention is not restricted to any particular temperature and pressure since the process may be operated successfully at temperatures and pressures selected from quite wide ranges. Thus, temperatures may range from about room temperature to about 300° F. The pressures may be sufficient for a liquid phase reaction, although it is possible to operate in the gas phase with paraffin hydrocarbons or hydrocarbon mixtures boiling at or below the temperature employed and

under atmospheric or subatmospheric pressures.

The proportion of isoparaffin is influenced by the operating conditions and the nature of the charge. Larger amounts of isoparaffin are advantageous when using higher temperatures and higher percentages of promoter and catalyst. Also when using the higher molecular weight charge stocks it is desirable to use higher ratios of isoparaffin.

It is contemplated that the isoparaffins may vary from about 25% by volume of the hydrocarbon charge up to 1000% or more, and preferably a ratio of isobutane to hydrocarbon charge from about 1:1 to 5:1.

For purposes of illustration and without in any way limiting the invention, examples are given below of the treatment of straight run gasoline in the presence of aluminum chloride and hydrogen chloride, with and without the addition of isobutane. Example I is a batch operation, without the addition of isobutane. Example II is an operation similar to Example I except isobutane is added according to the invention. Example III is a continuous operation using added isobutane in accordance with the invention. In Examples II and III the gasoline was converted into a product of improved volatility and anti-knock value with substantially no loss from catalyst deterioration, whereas in Example I the gasoline was impaired in volatility and there was a substantial loss in the form of a liquid complex of hydrocarbon and deteriorated catalyst.

Example I

A straight run gasoline from Mid-Continent crude oil was mixed with 20% of granular aluminum chloride, and 2.5% of HCl by weight. The mixture was agitated for 3 hours at about 198° to 204° F.

The percentage of the gasoline charge recovered as gasoline and off-gas was 86.8%. The amount of hydrocarbons in the gasoline charge combined with the catalyst to form a dark reddish colored liquid aluminum chloride-hydrocarbon complex containing all of the catalyst was 11.1%. The remaining products comprised HCl and gases lost during the reaction.

The tests on the original gasoline and gasoline product after stabilization, are as follows:

Before treatment with AlCl ₃	10% A. S. T. M. distillation	After treatment with AlCl ₃
130	I. B. P.....	91
168	5%	120
180	10%	135
198	20%	160
211	30%	184
222	40%	204
232	50%	225
240	60%	241
250	70%	259
260	80%	280
274	90%	366
284	95%	
309	E. P.....	502
99.0	Percent rec.....	96.0
1.0	(Percent res.....)	0.9
	(Percent loss.....)	3.1

	C. F. R. M. knock rating	
53.9	No. tetraethyl lead.....	67.5
65.0	1 cc. tetraethyl lead.....	70.4
73.0	2 cc. tetraethyl lead.....	83.5

Example II

Another sample of the same gasoline as used in Example I was agitated with 20% by weight of granular aluminum chloride, 5.1% by weight of HCl and about 386% by weight of isobutane based on the gasoline charged, in a pressure autoclave for three hours at about 190° to 200° F.

The products consisted of a gasoline and isobutane layer and a catalyst layer which differed from Example I in that the catalyst layer was not a liquid but a granular solid much the same as the original aluminum chloride.

The untreated and stabilized treated gasolines tested as follows:

Untreated	10% A. S. T. M. distillation	Treated
130	I. B. P.....	90
168	5%	138
180	10%	158
198	20%	192
211	30%	210
222	40%	222
232	50%	232
240	60%	242
250	70%	252
260	80%	268
274	90%	296
284	95%	
309	E. P.....	374
99	Percent rec.....	95.5
1	(Percent res.....)	0.9
53.9	(Percent loss.....)	3.6
	C. F. R. M. octane number	63.3

The volatility of the upper portion of the distillation range is improved over Example I above, and the end point is within the gasoline range.

Example III

A straight run Mid-Continent naphtha, similar to that in the preceding examples, and isobutane in the ratio of about four parts isobutane by volume to one of naphtha, and about 0.5% by weight of HCl based on the mixture, is continuously fed to a tower containing aluminum chloride wherein the mixture is contacted with the catalyst at about 190° to 210° F. After separating any complex and catalyst, the reaction products are subjected to debutanization to separate the gases, containing isobutane and HCl, which are recycled. About 95% to 99% of the naphtha with an octane increase of about 10 points is recovered.

The invention is applicable to the treatment of various fractions of normally liquid paraffin hydrocarbons, such as pentane, hexane, heptane or octane, or mixtures of two or more thereof as well as virgin naphthas of various boiling ranges.

The invention will be further understood from the accompanying drawing which shows a diagrammatic sketch of one form of apparatus for carrying out continuously the process of the invention.

Referring to the drawing, the charge stock is introduced through the line 1 by the pump 2 into catalyst chamber or tower 4 containing the catalyst 5. Any liquid complex or partially spent catalyst in reactor 5 may be withdrawn from this reactor through line 6. The aluminum chloride contained in the complex may be recovered by destructive distillation of the complex. The reaction products are transferred from the upper portion of the catalyst chamber through the line 7 to a separator 8 wherein any catalyst carried over in solution with the hydrocarbons from the catalyst chamber may separate and be withdrawn from the lower portion of the separator through the line 10, or other suitable means of removal.

The separator, or the reaction products entering the separator, may be cooled to facilitate precipitation of the catalyst. The hydrocarbons are passed from the separator through the line 11 to a debutanizer or fractionator 12 wherein the hydrogen chloride and normally gaseous hydrocarbons, comprising chiefly isobutane, are separated and removed overhead through the vapor line 15 and condenser 16. If isopentane is used instead of or with the isobutane, it may also be removed all or in part with the overhead from the fractionator 12. The overhead products may be recycled all or in part through the line 18, pump 19 and line 20 to the catalyst chamber. In case the products removed overhead from the debutanizer 12 contain constituents which are undesirable for recycling, such as propane, it may be desirable to remove such materials or to discard a fraction in order to prevent them from building up in the system. For this purpose, any portion of the products may be passed through the line 21 by the pump 22 to a fractionator 24. In the fractionator a separation is made between isobutane and/or isopentane and lighter gases which are released from the upper portion of the fractionator through the line 25. The isobutane fraction is withdrawn from the lower portion of the fractionator through the line 26 and may be passed all or in part through the line 38 by the pump 37 for recycling. If desired, hydrogen chloride may be recovered from the light gases withdrawn from fractionator 24 through line 25, and recycled to reactor 5.

The debutanized hydrocarbons are withdrawn from the bottom of the debutanizer through the line 28, pump 29 and line 30 to a fractionator 31. In the fractionator 31 the products are fractionally distilled to separate the gasoline fraction from bottoms which are withdrawn from the lower portion of the fractionator through the line 32. The gasoline vapors are removed overhead from the fractionator through the line 33 and condenser 34 to an accumulator 35.

Obviously many modifications and variations of the invention, as hereinbefore set forth, may be made without departing from the spirit and scope thereof, and therefore only such limitations should be imposed as are indicated in the appended claims.

We claim:

1. A process for improving the antiknock value of naphtha rich in normal paraffins which comprises subjecting the naphtha to contact with a metallic halide isomerization catalyst normally tending to deteriorate and form hydrocarbon complex, and effecting the contact treatment at an isomerizing temperature not in excess of about 300° F. and in the presence of an added isoparaffin of the class of isobutane and isopentane in amount by weight substantially in excess of the weight of the naphtha feed and such that naphtha feed hydrocarbons are isomerized to products of improved antiknock value without substantial catalyst deterioration and with relatively little conversion to hydrocarbons boiling below and above the boiling range of the naphtha feed.

2. The method according to claim 1 in which the catalyst comprises aluminum chloride and hydrogen chloride.

3. The method according to claim 1 in which the catalyst comprises aluminum chloride and hydrogen chloride and the contact treatment is effected at a temperature of about 190 to 210° F.

4. The method according to claim 1 in which the isoparaffin and the naphtha are charged to

the reaction in the proportion of from about four to ten volumes of isoparaffins to one volume of naphtha.

5. A process for the isomerization of naphtha hydrocarbons which comprises continuously passing a stream of naphtha feed hydrocarbon through a reaction zone containing an isomerization catalyst maintained under conditions such that isomerization constitutes the principal reaction and such that the reaction is normally accompanied by formation of a small amount of material boiling above the gasoline boiling range, continuously introducing to said zone a stream of low boiling isoparaffin hydrocarbon in an amount sufficient to maintain therein low boiling isoparaffin in an amount substantially greater by volume than the naphtha feed undergoing treatment therein and sufficient at least to substantially reduce the formation of said high boiling material, effecting substantial isomerization of naphtha feed in the presence of the added low boiling isoparaffin at a temperature not in excess of about 300° F. with substantial reduction in cracking and catalyst deterioration over that obtaining when the reaction is effected in the absence of added low boiling isoparaffin, and continuously removing from the reaction zone a reacted hydrocarbon mixture containing isomerized naphtha hydrocarbons.

6. The process according to claim 5 in which the catalyst comprises metallic halide activated with hydrogen halide.

7. The process according to claim 5 in which the low boiling isoparaffin hydrocarbon maintained in the reaction zone consists essentially of isobutane.

8. The process according to claim 5 in which the low boiling isoparaffin maintained in the reaction zone amounts to at least about 400% by volume of the naphtha feed hydrocarbon undergoing treatment.

9. A process for the isomerization of naphtha hydrocarbons which comprises continuously passing a stream of naphtha feed hydrocarbon through a reaction zone containing an isomerization catalyst maintained under conditions such that isomerization constitutes the principal reaction and such that the reaction is normally accompanied by formation of a small amount of material boiling above the gasoline boiling range, continuously introducing to said zone a stream of low boiling isoparaffin hydrocarbon in an amount sufficient to maintain therein low boiling isoparaffin in an amount substantially greater by volume than the naphtha feed undergoing treatment therein and sufficient at least to substantially reduce the formation of said high boiling material, effecting substantial isomerization of naphtha feed in the presence of the added low boiling isoparaffin with substantial reduction in cracking and catalyst deterioration over that obtaining when the reaction is effected in the absence of added low boiling isoparaffin, and continuously removing from the reaction zone a reacted hydrocarbon mixture containing isomerized naphtha hydrocarbons.

10. In a continuous process for the isomerization of naphtha hydrocarbons in a reaction zone containing an isomerization catalyst maintained under conditions such that isomerization constitutes the principal reaction and such that the reaction is normally accompanied by formation of a small amount of material boiling in the range above gasoline, the steps comprising continuously passing a stream of naphtha feed hydrocarbons to

said reaction zone, subjecting it therein to contact with the catalyst in the presence of a low boiling isoparaffin, added to the reaction, effecting substantial isomerization of naphtha feed hydrocarbons with substantial reduction in cracking and catalyst deterioration over that obtained when the reaction is effected in the absence of added low boiling isoparaffin, continuously discharging from the reaction zone a stream of isomerization naphtha hydrocarbons and added low boiling isoparaffin, separating from the dis-

charged stream an isoparaffin fraction lower boiling than said isomerized naphtha hydrocarbons and recycling said separated isoparaffin fraction to the reaction zone in an amount sufficient to provide therein low boiling isoparaffin in an amount substantially greater by volume than the naphtha feed undergoing treatment therein and sufficient at least to substantially reduce the formation of said high boiling material.
